OXYGEN ADMINISTERING MASK UNIT

William W. Hansford, Jr., Kansas City, Mo., assignor to
Puritan Compressed Gas Corporation, Kansas City,
Mo., a corporation of Missouri

Filed Jan. 30, 1967, Ser. No. 5,602

Term of patent 14 years

(Cl. D83—1)

FIG. 1 is a front elevational view of an oxygen administering mask unit, showing my new design with the tube member broken away in part to indicate indeterminate length;

FIG. 2 is a side elevational view thereof;

FIG. 3 is a top plan view thereof as shown in FIG. 2;

FIG. 4 is a rear elevational view thereof as shown in FIG. 2; and

FIG. 5 is a bottom plan view of the oxygen administering mask unit.

The fragmentary bag member shown in FIGS. 1, 2 and 4 and the conventional indicia disclosed in FIG. 4 are shown in broken lines for illustrative purposes only.

I claim:

The ornamental design for an oxygen administering mask unit, as shown and described.
